METHOD OF AND MEANS FOR TREATING
HEART AILMENTS

Aldo A. Luisada, Boston, Mass.

Application March 23, 1943, Serial No. 480,133

7 Claims. (Cl. 128—298)

This invention relates to a method of and means for treating certain heart diseases or ailments, particularly congestive heart failure and shock.

In accordance with the present invention, the patient is completely enclosed within a chamber and the atmospheric pressure within the chamber is rhythmically decreased and increased in synchronism with the systole and diastole of the heart, the atmospheric pressure being decreased below normal atmospheric pressure during ventricular systole and increased above normal atmospheric pressure during ventricular diastole whereby there is a decrease in the resistance to the movement of the blood from the heart to the different parts of the body during ventricular systole and whereby a positive force is provided for moving the blood toward the heart from the various parts of the body during ventricular diastole. The increase in atmospheric pressure within the chamber above normal atmospheric pressure is of the order of 5 millimeters of mercury and the decrease in atmospheric pressure within the chamber below normal atmospheric pressure is also of the order of about 5 millimeters of mercury. More particularly, in accordance with the present invention, provision is made for decreasing the pressure under the control of the R wave of the electro-cardiograph of the patient in such manner that decrease of pressure occurs during ventricular systole and increase of pressure occurs during ventricular diastole.

The present invention and the manner of practicing the same will best be understood from the following description, reference being had to the accompanying illustrative drawing.

In the drawing:

Fig. 1 is a view illustrating the method of the present invention and illustrating, more or less diagrammatically, apparatus for use in practicing the method;

Fig. 2 is a view on the line 2—2 of Fig. 1;

Fig. 3 is an electro-cardiogram;

Fig. 4 is a sectional view of a clutch which may be used in the apparatus.

Referring now to the drawing in detail, there is illustrated in Fig. 1 a chamber 10, such as a small room, within which the patient is completely enclosed so that all parts of the patient's body are subjected to variations in atmospheric pressure within the chamber. The pressure within chamber 10 is alternately decreased and increased under the control of the electro-cardiograph 12 which is operatively connected to the patient within the chamber as illustrated dia-

grammatically in the drawing. More particularly, in the apparatus here shown, the interior of chamber 10 is placed in communication by means of a valve 14 alternately with a source of low pressure and with a source of high pressure, respectively. Thus, as here shown, valve 14 is mounted for reciprocation in a valve chest 16 which communicates with chamber 10 through a conduit 18 and with low pressure and high pressure sources through conduits 20 and 22, respectively. Valve 14 has a single port 24 which registers alternately with the low pressure and high pressure inlet ports 26 and 28, respectively, of valve chest 16.

15 Valve 14 is provided with a stem 30 which is engaged by a spring 32 which moves valve 14 to the position thereof in which port 24 registers with the high pressure inlet port 28. The lower end of valve stem 30 is engaged by a rotary cam 20 34 which during the rotation thereof moves valve 14 to a position in which port 24 thereof registers with the low pressure inlet port 26, at which time the high pressure inlet port 28 is closed by said valve. Cam 34 is rotated by a shaft 36 which 25 is connected to a drive shaft 38 through a clutch 40, shaft 38 being continuously rotated during the operation of the apparatus in any suitable way as by the electric motor M. Clutch 40 comprises a driving clutch member 42 which is slid 30 able longitudinally of shaft 38 and is constantly rotated thereby. The companion clutch member 44 is fixed to the driven shaft 38 in position for the engagement and disengagement thereof by the driving clutch member 42. Driving clutch member 42 is engaged with and disengaged from driven clutch member 44 by a pivoted lever 46 operated by an electric relay. It will be understood 35 that clutch 40 includes a spring 47, as in any conventional clutch, which normally holds driving clutch member 42 out of engagement with driven clutch member 44, and that when relay 48 is energized the armature arm 50 of lever 46 is attracted so that said lever is actuated for moving driving clutch member 42 into engagement with driven clutch member 44. It will be understood 40 that when relay 48 is de-energized, the driving clutch member 42 is shortly thereafter disengaged by the clutch spring from driven clutch member 44. It will be understood that shaft 38 rotates at a high speed and that when clutch 40 is engaged the speed of rotation of cam 34 is likewise high for operating valve 14 during the short periods of heart systole and diastole.

45 Relay 48 is operated under the control of the 50 electro-cardiograph 12 and as here shown is con-

nected thereto through the filter 52 and the amplifier 54. Filter 52 passes only the R wave of the electro-cardiograph, which wave is amplified by the amplifier 54, said wave being as usual of the general form illustrated in Fig. 3 and occurring before contraction of the heart ventricles. Accordingly the winding of relay 48 is energized only by the amplified R wave of the electro-cardiograph. As the R wave of the electro-cardiograph slightly precedes the beginning of ventricular systole, relay 48 is energized by said R wave at the proper time for effecting the rotation of cam 34 for moving valve 14 to the position thereof in which its port 24 registers with the low pressure inlet port 26 of the valve chest, thus placing the interior of chamber 10 in communication with the source of low pressure whereby to lower the pressure in said chamber during ventricular systole. Immediately following the lowering of pressure during ventricular systole, relay 48 is de-energized under the control of the R wave, and by that time the cam projection 56 has been moved out of engagement with the cam follower 58 of valve stem 30, so that spring 32 moves valve 14 to the position thereof in which port 24 registers with high pressure inlet port 28 whereby the interior of chamber 10 is placed in communication with the high pressure source, thus resulting in increase of pressure in said chamber during ventricular diastole. This cycle is repeated at regular intervals in accordance with the occurrence of the R wave of the electro-cardiogram.

It will be understood that means other than that herein illustrated or described may be utilized for controlling the atmospheric pressure within chamber 10 under the control of means responsive to the systolic and diastolic actions of the heart of the patient. Accordingly, I do not wish to be limited to the apparatus herein specifically shown or described except to the extent which may be required by the scope of the appended claims.

Having thus described my invention, what I claim and desire to secure by Letters Patent is:

1. Means for use in the treatment of heart ailments comprising a chamber for completely enclosing the patient, means responsive to the systolic and diastolic actions of the heart of the patient, and means operable under the control of said last mentioned means for varying the air pressure in said chamber in rhythmic relation to said actions of the heart.
2. Means for use in the treatment of heart ailments comprising a chamber for completely enclosing the patient, an electro-cardiograph adapt-

ed to be operatively connected to the patient in said chamber, a filter for passing only the R wave of said electro-cardiograph, a relay operatively connected to said filter, and means operable under the control of said relay for varying the air pressure in said chamber in rhythmic relation to said actions of the heart.

3. Means for treating a heart ailment of a patient enclosed in a chamber, comprising an electro-cardiograph adapted to be operatively connected to the patient in said chamber, and means operable under the control of said electro-cardiograph for varying the air pressure in said chamber in rhythmic relation to said actions of the heart.

4. The method of treating heart ailments which comprises enclosing the patient completely within a chamber, connecting an electro-cardiograph to the patient in said chamber, decreasing the pressure in said chamber under the control of said electro-cardiograph during systole of the patient's heart and increasing the pressure in said chamber under the control of said electro-cardiograph during diastole of the patient's heart.

5. Means for use in the treatment of heart ailments comprising a chamber for completely enclosing the patient, an electro-cardiograph adapted to be operatively connected to the patient in said chamber, and means operable under the control of said electro-cardiograph for connecting said chamber alternately to sources of low pressure and high pressure, respectively, during the periods of systole and diastole, respectively, of the patient's heart.

6. Means for treating a heart ailment of a patient enclosed in a chamber, comprising means responsive to the systolic and diastolic actions of the heart of the patient, and means operable under the control of said last mentioned means for connecting said chamber alternately to sources of low pressure and high pressure, respectively, during the periods of systole and diastole, respectively, of the patient's heart.

7. Means for treating a heart ailment of a patient enclosed in a chamber, comprising an electro-cardiograph adapted to be operatively connected to the patient in said chamber, a filter for passing only the R wave of said electro-cardiograph, a relay operatively connected to said filter, and means operable under the control of said relay for connecting said chamber alternately to sources of low pressure and high pressure, respectively, during the periods of systole and diastole, respectively, of the patient's heart.
